(57) **CLAIM**

The ornamental design for a manifold engagement portion of a filter cartridge, as shown and described.

DESCRIPTION

FIG. 1 is top, front, and right side perspective view of a manifold engagement portion of a filter cartridge;

FIG. 2 is another top, front, and right side perspective view of the first embodiment of a manifold engagement portion of a filter cartridge;

FIG. 3 is a top view of the first embodiment of a manifold engagement portion of a filter cartridge; and,

FIG. 4 is a bottom view of the first embodiment of a manifold engagement portion of a filter cartridge.

The broken lines in FIGS. 1-4 are for the purpose of illustrating environmental structure and forms no part of the claimed design thereof.

1 Claim, 2 Drawing Sheets
